UNITED STATES PATENT OFFICE.

ALBERT EDWARD HORLICK PAYNE, OF KILDARE, IRELAND.

ENVELOP AND THE LIKE.

1,335,183.

Specification of Letters Patent. Patented Mar. 30, 1920

Application filed August 28, 1918. Serial No. 251,506.

To all whom it may concern:

Be it known that I, ALBERT EDWARD HORLICK PAYNE, contractor, a subject of His Majesty the King of Great Britain and Ireland, residing at Mons Leinster Walk, Kildare, Ireland, have invented certain new and useful Improvements in or Relating to Envelops and the like; and I do hereby declare the following to be a full, clear, and exact description, such as will enable others skilled in the art to which it appertains to make and use the same.

This invention relates to a novel and convenient appliance retainable in a fold at the perimeter of an envelop or its like. While 15 susceptible of modification (as will hereinafter appear) my invention in every case comprises a length of string or like flexible substance retained for use in a fold at the perimeter of an envelop or its like whereby to 20 tear said fold a hold is given.

The object of my invention herein set forth is to provide the cutting string at the perimeter of a slip of cardboard or other 25 suitable material to which it is attached throughout the length of the edge so that when this slip is within the envelop with the 30 end or ends of its string projecting through the corresponding corner or corners of the envelop the fold line or crease between these limits may be slit by the operator tearing back the end of the string in the usual 35 manner thereby at the one and same operation tearing the string from the slip and tear the envelop fold aforesaid.

In order that my invention may be clearly understood I will now describe the same with reference to the annexed drawing wherein—

40 Figure 1 is a sectional view of a fold at the perimeter of an envelop or its like containing a slip of cardboard or other suitable material in accordance with my invention and Fig. 2 is a face view of the same. Fig. 45 3 is a detail referring thereto.

Similar numerals refer to similar parts throughout the several views.

Referring to Fig. 1: 1, 2, 3, show the fold formed by the material (of which the envelop or its like is made) being folded at 2

a perimeter thereof and therein is part of a length of string or like flexible substance 4 attached to a slip of cardboard or other suitable material 6 by means of a strip of adhesive paper 7 or other suitable means. 55 Where appearance is of less importance than utility I may be content to tie string 4 to the edge of slip 6.

Referring to Fig. 2: 1 shows the face of and 2, 2 that part of the perimeter referred to in Fig. 1 indicating position of string 4 and by rectangle of dotted lines the slip 6 which notwithstanding limits there shown may be of any dimensions within the capacity of the envelop or its like. I prefer that 60 same to be one-quarter of an inch smaller than the pocket intended for it. Any disadvantage that the said slip may have by reason of its presence in the envelop may be more than compensated by using its body 70 for some pleasing or useful purpose such as picture calendar advertisement or even to contain the message so sent.

Referring to Fig. 3: Here slip 6 is shown with the string 4 in a fold at its perimeter 75 so held by adhesive.

In the case of small envelops I prefer paper slip 6 and the string 4 may in such case be in a fold formed on perimeter of the same similar to that shown in Fig. 3 instead of strip 7.

As another modification of the foregoing I may fasten string 4 on a strip of adhesive paper or other suitable material and affix the same at perimeter of slip 6. 85

Consideration for substance and make of the envelop or its like proposed to be used must decide the best modification therefor. Therefore I do not confine or limit myself to either or any one particular means for retaining said length of string or like flexible substance at the perimeter of the aforesaid slip 6 or to the dimensions of or nature of the said string or like flexible substance to be used thereon.

What I claim and desire to secure by Letters Patent of the United States is:—

In a device of the character described a cutting string at the edge of a slip of paper to which it is attached throughout the length 100

of the edge so that when this slip of paper is within the envelop with its string bearing edge in the fold thereof and the end of the string projecting through the corresponding corner of the envelop the said fold may be slit by the operator pulling back the end of the string in the usual manner thereby at the one and same operation tearing the

string from the slip and tearing the envelop fold aforesaid substantially as set forth.

In testimony whereof I affix my signature in the presence of two witnesses.

ALBERT EDWARD HORLICK PAYNE.

Witnesses:

LENA PAYNE,
C. HUMPHRIES.
